UNITED STATES PATENT OFFICE

2,656,188

BOWLING BALL GRIP STRUCTURE

Vernon L. Anderson, Kansas City, Mo., assignor
of one-half to Paul W. Christensen, Kansas
City, Mo.

Application April 30, 1951, Serial No. 223,786

3 Claims. (Cl. 273—63)

1

This invention relates to improvements in bowling balls and particularly in the grip structure therefor and has for its primary object the provision of means of ventilating one of the finger-receiving openings thereof, particularly the cavity for receiving the thumb and including an opening formed in the ball itself for placing the thumb cavity in register with the atmosphere.

Those familiar with the game of bowling and particularly the experts, are well aware of the fact that a firm grip on the bowling ball is highly essential to proper control and ease of playing. The grip structure of conventional bowling balls being fully unventilated, causes slippage due to perspiration and mere roughening of the inner surfaces of the finger-receiving cavities is not capable of overcoming the problem.

Accordingly, it is the most important object of the present invention to provide air inlet means for the finger cavity of bowling balls and including a plurality of substantially radial openings having lateral passages or branches communicating directly with the thumb-receiving cavity.

A further object of this invention is to provide a bowling ball grip structure wherein the aforesaid air-receiving holes or openings and passages terminate in register with the thumb-receiving cavity at the point of contact of the thumb with the ball in the cavity so as to additionally increase the grip.

More minor objects will become clear as the following specification progresses, reference being had to the accompanying drawing, wherein:

Figure 1 is an elevational view of a bowling ball, parts being broken away and in section to reveal the novel grip structure of the present invention; and

Fig. 2 is an enlarged plan view showing the thumb-receiving cavity and illustrating the arrangement of the grip structure hereof.

The bowling ball illustrated in the drawing is broadly designated by the numeral 10 and includes a spherical body that may be made from any suitable material such as wood, plastic or rubber such as is quite common and having grip structure that includes a plurality of finger-receiving cavities, two of which are illustrated in Fig. 1, and designated by the numerals 12 and 14 respectively.

All of the openings are disposed substantially 50 radially and the opening 12 for receiving finger 16 of a hand 18 of a player is normally shorter than the opening 14 for receiving thumb 20.

In order to ventilate the thumb-receiving opening 14 and to present a roughened surface 22 55

2

within the cavity 14 against which the thumb 20 engages, there are provided a plurality of elongated openings 24 adjacent the cavity 14, each of which in turn is provided with a number of laterals or branches 26 that terminate within the wall portion 22 of cavity 14 and place the openings 24 in direct communication with cavity 14.

It is seen in Fig. 2 of the drawing that the openings 24 are preferably arranged in a semi-circular row and as shown in Fig. 1, the openings 24 are substantially radial and preferably have their longitudinal axes parallel with the longitudinal axis of cavity 14. The innermost ends of the openings 24 may terminate short of the inner end of cavity 14 and the plurality of spaced branches 26 are preferably disposed with their longitudinal axes parallel and perpendicular to the longitudinal axes of openings 24 and cavity 14.

It is now apparent that through use of the novel improvement in grip structure for bowling balls forming the subject matter hereof, the thumb-receiving cavity 14 is fully ventilated at all times and by virtue of the air that is permitted to enter the cavity 14 through the openings 24 and laterals 26, the tendency for perspiration to form on thumb 20 is reduced tremendously. Furthermore, by virtue of the lateral branches 26 opening within the cavity 14, and particularly along wall 22 thereof wherein thumb 20 engages the bowling ball 10, a roughened surface is presented that increases the grip that is made possible on surface 22 by thumb 20.

Another advantage results in the cooperation of the air within the laterals 26 trapped at least temporarily by the thumb 20 closing the passages 26 and thereby increasing the grip of thumb 20 on the ball 10.

Variances in details of construction that fairly 40 come within the spirit of this invention are manifestly contemplated hereby and it is, therefore, desired to be limited only by the scope of the appended claims.

Having thus described the invention what is 45 claimed as new and desired to be secured by Letters Patent is:

1. In a bowling ball, a spherical body having a number of finger-receiving cavities, and an arcuate row of openings adjacent one cavity, each opening registering with the atmosphere and having a number of lateral passages connecting the same with the one cavity.

2. In the invention as set forth in claim 1, wherein at least one of the passages of at least one of the openings registers with the cavity at a

zone of finger contact to present an anti-slip, finger-engaging surface in the cavity, and at least one other of the passages of at least one of the openings registers with the cavity at a point spaced from said zone to provide a vent for the cavity.

3. In a bowling ball, a spherical body having at least one elongated finger-receiving cavity, at least one vent opening, and a row of lateral passages interconnecting the opening with the cavity 10 and disposed longitudinally of the latter, certain of the passages registering with the cavity at a zone of finger contact to present an anti-slip,

finger-engaging surface within the cavity, other of the passages registering with the cavity remote from said zone to present venting means for the cavity.

VERNON L. ANDERSON.
